UNITED STATES PATENT OFFICE

HENRY W. BORCHERS, OF PORTLAND, OREGON.

AUTOMATIC FIRE-LIGHTER.

SPECIFICATION forming part of Letters Patent No. 425,740, dated April 15, 1890.

Application filed July 20, 1889. Serial No. 318,165. (No model.)

To all whom it may concern:

Be it known that I, HENRY W. BORCHERS, of Portland, in the county of Multnomah and State of Oregon, have invented a new and useful Improvement in Automatic Fire-Lighters, of which the following is a full, clear, and exact description.

My invention relates to an improvement in automatic fire-lighters, and particularly to a class in which an ordinary portable alarm-clock is utilized to actuate the lighting mechanism at a proper instant of time.

The object to be attained by my present invention is the production of a reliable, cheap, and simple device, which is portable and readily attachable to any small alarm-clock, and when so attached is capable of lighting a fire in a stove or grate at any predetermined moment of time.

With these objects in view my invention consists in certain features of mechanical construction and combinations of parts, which will be hereinafter fully described, and pointed out in the claims.

Reference is to be had to the accompanying drawings, forming a part of this specification, in which similar letters of reference indicate corresponding parts in all the figures.

Figure 1 is a side elevation of the device with an alarm-clock in position to operate the lighting mechanism. Fig. 2 is a plan view of the lighting device connected to a clock-alarm. Fig. 3 is an end elevation of the lighting device connected to the alarm. Fig. 4 is a transverse section in elevation of the lighting device and an alarm-clock attached thereto, the case of the clock being broken away to show the manner of connecting the alarm to the lighter. Fig. 5 is a view in elevation of an attachable stand which may be used to afford support to the lighting device and an attached alarm-clock.

A represents the base-plate of the device. It is metallic and of a convenient size to support all parts of the apparatus. Upon the base-plate an adjustable post C is erected. It is held in place by a clamping thumb-screw L, which, when slackened, will allow the post to be slid in the slot e', and so permit a proper adjustment of the post on the base-plate A.

A perforated hub a is placed upon the upright post C, and adjustably secured at any

desired point by the thumb-screw b. Integral with the hub an arm D projects laterally from the same having a clasp or hoop spring 55 E, attached to its upper surface near the free end g. Said clasp E is of such relative dimensions and strength as to embrace the cylindrical body of a portable alarm-clock F and retain it in position, as shown in Fig. 2. 6c

Adjacent to the supported clock F, a short hollow post or column B is erected from the base-plate A, so as to be opposite the rear side of the clock, (see Fig. 4,) and from its base near the axial center of the same an 65 upright shaft O is erected. A locking-disk K is secured near the top end of the shaft O, said terminal end having a support in the cross-bar p, which is integral with the column B, and extends across the same at its upper 70 end. The spiral spring o loosely embraces the shaft O, and has its lower terminal hooked fast to the base-plate of the column B, the upper end of said spring being secured to the locking-disk K. 75

From the peripheral edge of the locking-disk K a toe n projects, as shown in Fig. 2, which toe is of sufficient length to abut against the upturned end m' of the curved spring m, the latter being attached at its opposite end 80 m² to the side of the upright column.

The action of the spring m is designed to be vibratory, horizontally considered, so that when the spring o is wound around the shaft O to give it proper resilience and the toe n 85 of the locking-disk k is engaged by the spring m in the manner stated it will require a downward vibration of the locking-spring m to release its connection with the toe n, and so permit the disk k to revolve. 90

From the locking-disk k an arm G projects laterally through an elongated slot i made in the wall of the column B. Said arm is of such a length as to permit it to swing around and lie near to the grate M of a stove or range, as 95 will be further explained.

Upon the outer extremity of the arm G a clamp c is formed, which is designed to receive and securely hold in a vertical position depending from it the match H, that is embraced at its upper end by the split portions or jaws of the clamp, and therein retained by the compression-screw c', which draws the clamp-jaws together. 100

From the side of the column B, near its upper edge, a laterally-projecting sleeve J affords support to the rock-shaft S, permitting it to vibrate therein. On the inner end 5 of the rock-shaft S an integral lug h is formed, which projects therefrom and lies with its free end in contact with the spring m, the position of the lug being diagonal with regard to the engaged body of the spring m, so that 10 if the shaft S is rocked a proper distance the lug will depress the spring and release the toe n of the locking-disk K in an obvious manner. The outer end of the rock-shaft S is slotted across its center of sufficient depth to receive a tongue f, (see Fig. 2,) which latter is formed on the outwardly-projecting end 15 of the main shaft N of the alarm mechanism of the clock, and as this mechanism is of any approved style preferred it is not shown. The construction of such a device, being well known, does not constitute a part of my invention.

The shaft N of the alarm apparatus is adapted to rotate by its driving-spring in the usual way; hence if the tongue and slotted connection of this shaft with the rock-shaft S is effected by simply sliding them together and securing the clock in the manner stated 20 it is evident that when the alarm is put in motion at any predetermined time set for its discharge the arm G will be released and made to swing around, as previously mentioned.

In the path of travel of the attached match H a scratch-block I is projected upwardly from the base-plate A of such a relative height 25 that a properly-secured match will impinge upon its roughened top surface d', and by the frictional contact of its "head" therewith be ignited while it passes over the same.

A portion d of the top surface of the block I is not roughened. (See Fig. 1.) Upon this smooth face the end of the match may rest 30 when it is being inserted and clamped, and as the roughened portion is slightly higher than the face d it is evident that a correct 35 position can be given the match-head to insure its ignition.

The entire fixture is intended to rest upon the hearth-plate or apron of a stove or range, 40 so that the match H will approach the bars of the grate and come in contact with and ignite combustible materials placed within the grate and projected therefrom, such as paper or shavings, which latter by their combustion 45 will inflame wood or similar materials within the grate, and thus start a fire therein at any time required. The operation is automatic and controlled by the previous "setting" of the alarm of the clock to discharge 50 its mechanism, ring a bell, and simultaneously 55 actuate the fire-lighting device.

In some cases it may be required to employ the fire-lighting device to start a fire in a stove, 60 range, or grate having no hearth-plate whereon to rest the bed-plate of the apparatus. To this end a stand (shown in Fig. 5) is provided. It rests upon the floor of the apartment near

the place where the fire is to be started and engages with its upright rod s the boss R, formed on the base-plate A, said boss being 70 perforated and provided with a set-screw to impinge upon the rod and hold the lighting device at a proper height.

Slight changes might be made in the mechanical details of this invention within its 75 manifest scope; hence I do not wish to restrict the same to the exact forms shown.

Having thus described my invention, what I claim as new, and desire to secure by Letters Patent, is—

1. In an automatic fire-lighter, the combination, with a base-plate, a revoluble shaft supported vertically, an arm projected from this shaft to be swung by a revoluble movement of the shaft, a locking-disk mounted on the shaft, a device to lock the disk and hold the arm, and a match-holding clamp, of a rock-shaft loosely secured to the main shaft of a clock-alarm and adapted to release the locking-disk when the alarm is discharged, 90 substantially as set forth.

2. In an automatic fire-lighter, the combination, with an alarm-clock removably supported on a base-plate and a base-plate, of a swinging arm, a locking device which holds the arm from swinging, a spring which moves the arm in a horizontal plane, a match-holding clamp attached to the free end of the arm, a scratching-block, and a rock-shaft which is removably connected with the main shaft of the alarm mechanism of a clock and is adapted to release the locking device which holds the swinging arm when said rock-shaft is rocked by the alarm mechanism, substantially as set forth.

3. In an automatic fire-lighter, the combination, with a swinging match-carrying arm, a device which supports and actuates this arm in a horizontal plane, a match-holding clamp, and a match - scratching block, of a rock-shaft having a lug on one end which engages the actuating mechanism of the swinging arm to release said arm, a tongue-and-groove connection between the other end of the rock-shaft and the main shaft of the alarm mechanism of an alarm-clock, and said main shaft, substantially as set forth.

4. In an automatic fire-lighter, the combination, with a base-plate, a supporting-stand which engages the base-plate, a scratching-block, a vertical shaft, a locking-disk, a spiral spring, and a swinging arm which is adapted to hold a match at its free end, of a detent curved spring which engages the toe of the locking-disk, a rock-shaft having a lug formed on one end which engages the detent-spring and has a tongue-and-slot connection at its other end with the main shaft of a clock-alarm, and said main shaft, substantially as set forth.

HENRY W. BORCHERS.
